signor to Teledyne, Inc., Hawthorne, Calif.

Filed Nov. 18, 1965, Ser. No. 88,146

Term of patent 14 years

(Cl. D26—14)

FIG. 1

FIG. 2

FIG. 3

FIG. 4

FIG. 1 is a left side, top and front perspective view of a telephone answering unit or similar article, showing my new design;

FIG. 2 is a front elevational view;

FIG. 3 is a top plan view; and

FIG. 4 is a right side elevational view thereof.

The undisclosed side of the telephone answering unit or similar article is substantially the same in appearance as the side shown, and the rear is substantially without ornamentation. The telephone desk stand and handset in FIG. 1 is for illustrative purposes only.

I claim:

The ornamental design for a telephone answering unit or similar article, as shown and described.
